DESIGN.

—o—
J. L. FOLSOM.

CARPET.

No. 18,126.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,126, dated March 6, 1888.

Application filed January 26, 1888. Serial No. 262,047. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

The characteristic feature of my design is the figure A, which is repeated continuously over the face of the carpet, as shown in the photograph. The figure A is a scroll-shaped 20 figure having a main or central curving stem,

the ends of which are curved into scroll forms. From this central stem project around the edges of the figure short stems or branches, which are also scrolled or curved. The general outline of the figure is therefore of a 25 scroll-like character. The figure is substantially oval in form, the spaces between the different parts of the scrolls being filled in with a shadow-work.

What I claim as new, and desire to secure 30 by Letters Patent, is—

1. The design for carpets, consisting of the figure A, substantially as shown.
2. The design for carpets, consisting of the figures A repeated, as described, substantially 35 as shown.

JAS. L. FOLSOM.
